MACHINE FOR SHAPING METAL WORKPIECES

Albert Maurice Redman, Croydon, England, assignor to Redman Tools & Products Limited, Croydon, England, a British company

Application January 26, 1951, Serial No. 207,879

10 Claims. (Cl. 153—46)

1

This invention comprises improvements in or relating to methods of shaping metal work-pieces and to metal-working machines therefor, and its object is to provide an improved method and construction of machine for the cold bending and shaping of work-pieces such as metal bars, rods, strips, tubes and the like, which method and machine are moreover particularly suitable for bending work-pieces into the form of a complete ring or closed figure, or for shaping those which are already in this form.

According to the present invention a method of shaping a metal work-piece consists in placing the work-piece against a former, pressing a shoe on to the work-piece toward the former, so that the shoe forces the work-piece to conform to the former at one part of its length, and thereafter while maintaining pressure on the shoe toward the former, shifting the place of application of such pressure progressively along the shoe and so rolling the shoe and former one over the other with the work-piece between them to cause the metal of the work-piece to flow into conformity with the shape of the former. Preferably the pressure on the shoe is hydraulically applied by a ram, the ram is pivotally mounted to swing about a centre located behind the former surface and the shifting of the place of application of pressure is effected by lateral movement of said pivotal centre.

The present invention further comprises in a metal-working machine the combination of a former, a press-member opposed to the former so as to bear on a work-piece placed on the former, a fluid-pressure-operated ram behind the press-member to urge it toward the former, a carrier on which the ram is mounted, said carrier having a fulcrum about which it is free to swing and the axis of which is located behind the former-surface, and means for moving the fulcrum to various positions to cause the carrier when pressure is applied to the work-piece, to swing and shift the place of application of pressure progressively along the work-piece.

Preferably the press-member comprises a shoe capable of rolling upon the work-piece against the former and the ram pressure acts against the back of the shoe to cause it to bear on the work-piece, and the ram may have a roller-nose to bear on the back of the shoe so that the nose can slide easily laterally along the shoe and the shoe can act progressively along the work-piece without lateral sliding movement thereon.

By progressively shifting the fulcrum of the ram carrier while the ram is applying pressure to the shoe it is possible to cause the nose of the ram to travel along the back of the shoe, the movement being somewhat analogous to sliding upon an inclined plane, so that the carrier swings about its fulcrum and the shoe rolls upon the work-piece. Thus the need for providing some independent means, such as a winch or hydraulic traversing cylinder, to haul or push upon the arm

2

to swing it is obviated and this fact is not only an advantage in itself but renders a machine according to the present invention particularly useful for shaping work in the form of complete rings or closed figures.

Moreover the provision of a shoe which rolls around the work-piece while the nose of the ram traverses the back of the shoe, in accordance with the construction described in co-pending patent application Serial No. 183,844, filed September 6, 1950, by Albert Maurice Redman and Arthur Frederick Frost, and issued April 28, 1953 as Patent No. 2,636,537 enables curved flanged work to be produced without undesirable distortion or crinkles. The shoe presses the work-piece against the former over a narrow area only at any one time and this narrow area of pressure is caused to travel slowly and progressively over the work-piece so that the metal of the work-piece flows and the work-piece is gradually smoothed or ironed to the shape of the former; the movement of the shoe must be slow enough to allow the cold metal time to flow and the result is that the finished form does not display any distortion or crinkles although the flanges of the work-piece show a very slight thickening toward their edges along the inside of the curve.

In the preferred form the movement of the fulcrum of the carrier is effected by two hydraulic piston and cylinder units acting in directions substantially at right-angles to one another. The carrier and ram may swing in a substantially horizontal plane, and the former may be carried by a central support depending from a bridge-member extending transversely over the machine at a height above the level of the carrier so that the carrier is able to pass beneath the bridge-member and swing through any angle up to 360° for the purpose of shaping work in the form of a complete ring.

One form of machine in accordance with the invention will now be described, by way of example, and with reference to the accompanying diagrammatic drawings in which:

Figure 1 is a diagrammatic plan view of the machine,

Figure 2 is a diagrammatic elevation in part section on the line 2—2 of Figure 1,

Figure 3 is a further diagrammatic plan view showing the parts in different relative positions to those of Figure 1,

Figure 4 is a diagram to illustrate the movements of the carrier and its fulcrum during operation of the machine,

Figure 5 shows a former block for the machine in plan view, and

Figure 6 is a diagram to illustrate further the operation of the machine.

The machine has a frame 11 comprising a base plate 12, side walls 13 and a rear wall 14. A bridge member 15 extends across the top of the machine near the front thereof between the side walls 13, and secured to the underside of

the bridge member midway along its length is a former support 40 carrying on its underside a male former 16 having a profile 17 which is elliptical in plan and semi-circular in vertical cross-section. The elliptical former is symmetrically mounted with respect to the bridge-member 15, with its major axis parallel to the side walls 13.

At the lower part of the machine two vertically spaced horizontal plates 18, 19 extend across the machine between the side walls and from the front to the rear, the lower plate 18 being supported at the front of the machine by a low vertical wall 20. A fulcrum block 21, which is circular in plan, slides horizontally between the two plates 18, 19 and has journalled in it a vertical pivot pin 22 disposed directly beneath the former 16, which pin serves as a fulcrum about which swings an elongated horizontal cantilever arm 23, shown extending forwardly of the machine in Figures 1 and 2. The circular fulcrum block has an internal cavity 24 through which the pivot pin 22 passes.

The cylinders 25, 26 of a pair of hydraulic piston and cylinder units are arranged horizontally between the plates 18, 19 and are pivotally connected to the machine frame, one near each rear corner of the frame. The cylinders have piston rods 27, 28 which extend towards the fulcrum block 21, the two piston and cylinder units being arranged very nearly at right-angles to one another as viewed in plan, and the rods 27, 28 pass into the cavity 24 within the block 21 through apertures in the wall surrounding the cavity. The piston rod 28 has an eye 29 and the piston rod 27 a forked eye 30, and the pivot pin 22 journalled in the fulcrum block 21 passes through the eyes 29, 30 the eye 29 being fitted between the forks of the eye 30. Thus it will be clear that the fulcrum block 21 and pivot pin 22 are movable bodily in any direction in a horizontal plane under the control of the two cylinders 25, 26, the upper horizontal plate 19 having an aperture 31 to allow the pivot pin to move laterally. The elongated arm 23 is therefore capable of swinging in a horizontal plane about its fulcrum 22 located within the closed figure of the profiled face of the former 16 in a manner to change the crossing angle of the longitudinal axis of arm 23 and the former profile and through a complete revolution of the former.

The arm 23 has secured along its upper surface a horizontal strap 32, and a second parallel strap 33 is spaced vertically above the strap 32 and is also secured to swing with the arm. The cylinder 34 of a horizontal hydraulic piston and cylinder unit is mounted between the outer ends of the straps 32, 33 and has a piston rod 35 extending parallel with the arm toward a vertical projection of the pivot pin 22. The axis of the piston rod 35 is on a level with the horizontal centre-line of the former profile 17, and the straps 32, 33 are spaced equi-distantly below and above the former respectively. Towards its inner end, that is the end nearer the pivot pin, the lower strap 32 is broadened out to form a table 36 which swings with the arm 23.

A shoe 37, for shaping the work-piece upon the former 16, is constituted by a heavy cast mild steel block, rectangular in plan and in cross-section, and resting horizontally upon the table 36 over which it is free to slide beneath the upper strap 33. The block 37 has a horizontal recess 38 extending along its surface which faces

towards the former 16, and three hardened steel inserts or liners 39 are fitted along the side and bottom faces of the recess, to resist wear and are so shaped that when they are in position the vertical cross-section of the recess, which is uniform along the whole length of the recess, is semi-circular to correspond to the shape of the outer or convex surface of the finished work which it is desired to produce upon the machine.

10 The longitudinal centre-line of the recess 38 is at the same height as that of the male former profile 16, and the shoe 37 with its longitudinal recess 38 constitutes a female former movable with respect to the male former 16, with which it cooperates to shape a work-piece held in place between the former 16 and the shoe.

15 The piston rod 35 of the piston and cylinder unit, mounted on the swinging arm 23, has at its inner end a forked adaptor 41 which carries a roller 42 mounted centrally of the arm 23 to rotate about a vertical axis, and under the action of the hydraulic cylinder 34 the roller 42 bears upon the back of the shoe 37 to cause the shoe to shape a work-piece against the former 16.

20 25 The operation of the machine will now be described. The pressure exerted by the hydraulic cylinder 34, clearly, always acts along the centre-line of the swinging arm 23 directly towards a vertical projection of the pivot pin 22; when this line of pressure is normal to the horizontal centre-line of the work-piece on the former 16 at that part thereof upon which the shoe 37 is bearing, the arm is stable and shows no tendency to swing, but if the line of pressure and the horizontal centre-line of said part of the work-piece on the former are at an angle to one another other than 90° then it will be seen that the force due to the pressure of the cylinder 34 can be resolved into a component normal to the former 16 and work-piece and a component parallel thereto, and the latter component of force tends to cause the arm 23 with the hydraulic pressure cylinder 34 to swing about its pivot 22. By moving the fulcrum block 21 under the control of the hydraulic cylinders 25, 26 it is possible to adjust the line of pressure of the cylinder 34 angularly with respect to the former 16 and work-piece until a point is reached when the aforesaid parallel component of force becomes sufficient to overcome the frictional forces of the parts and the resistance of the work-piece to the shoe 37 and therefore to swing the arm 23, and it will be realised that the arm 23 can be kept swinging, or stopped, or caused to swing in the reverse direction merely by effecting suitable movements of the fulcrum block 21, and that the speed of swing is controllable in the same manner.

25 30 Thus, by mounting the swinging arm 23 of the bending machine according to the present invention in such manner that the fulcrum block 21 is movable at will as desired, the need for providing independent means, such as a winch or hydraulic traversing cylinder, for swinging the arm by hauling or pushing upon it, as is often found in bending machines, is obviated. In the machine illustrated and described herein, the arm 23 and the pressure cylinder 34 it carries are capable of rotating through a complete revolution about the pivot pin 22 and around the former 16, the arm 23 passing beneath the bridge-member 15 and swinging in the space within the side walls 13 and rear wall 14 of the machine frame 11, and when the hydraulic cylinder 34 is exerting pressure the arm 23 may be caused to perform such a revolution, either in stages or continuously, as

desired, by effecting suitable movements of the fulcrum block 21 by means of the hydraulic cylinders 25, 26. The bending and shaping of a work-piece which is initially, or is to be finally, in the form of a complete closed figure, for example an ellipse, is therefore greatly simplified.

One mode of operating the particular machine described herein is as follows:

A metal work-piece in the form of a flat bar or band bent round into an endless elliptical ring with a plain cross-section is to be given a semi-circular cross-section (the machine is, of course, capable of bending a straight bar round into the form of an ellipse as well as shaping its cross-section in one and the same operation, but shaping of the cross-section of a work-piece will be considered here only, for the sake of simplicity). The dimensions of the profile periphery 17 and the inner dimensions of the ring to be shaped, as considered in plan view, are substantially the same, and the work-piece is placed around the elliptical former profile 16, after having first been dipped into a tank of drawing oil and allowed to drain, and is held temporarily in position thereon by any suitable means, for example by a clamp or clamps operated by hydraulic rams. The drawing oil serves to help keep the work-piece cool and lubricated during the subsequent forming operation. At the commencement of the forming operation the swinging arm 23 lies in the straight-ahead position shown in Figures 1 and 2, and the fulcrum of the arm 23 is upon the major axis of the former ellipse and is moved forward along said axis, by means of the hydraulic cylinders 25, 26, from the central position shown in Figures 1 and 2 to a position intermediate between said central position and the projected outline of the former profile 16 as viewed in plan. Figure 4 shows diagrammatically the movements of the swinging arm 23 and the fulcrum during the forming operation; the projected outline of the former is represented at 50, the central or neutral position of the fulcrum and swinging arm at 51 and 52, respectively, and the position of the swinging arm 23 and shoe 37 at the commencement of the forming operation is represented at 53. The position of the fulcrum on the major axis of the former ellipse and intermediate between the central position 51 and the projection of the former outline 50 is represented at 53 and the dotted line 51-53 indicates the path of the forward movement followed by the fulcrum.

The shoe 37 is positioned so that the right-hand end of it, as viewed looking along the arm towards the fulcrum, comes between the roller 42 and the former 16 with the work-piece thereon, and pressure is then applied by the cylinder 34 through the roller 42 to the back of the shoe 37 so that the shoe is forced toward the former 16 and driven tightly on to it around the work-piece, which is represented in Figures 1, 2 and 3 in phantom lines at 71, over a limited area in front of the roller. This action shapes the work-piece to the former profile and gives it the required semi-circular cross-section over part of the limited area of the work-piece with which the shoe is now in contact.

Movement of the fulcrum is then commenced in a rearward direction and toward the left as viewed from the front of the machine, along a path represented at 54 in Figure 4, and consequently the arm 23 is translated from the stable condition in which the line of pressure of the hydraulic cylinder is coincident with the major axis of the former 16 into an unstable condition

in which there is a component of force tending to move the arm 23 bodily to the left, and as the fulcrum continues its movement along the path 54 the frictional forces of the machine and the resistance of the work-piece to the shoe are overcome and the arm commences to swing round to the left, or in a clockwise direction as viewed in plan, and follows the fulcrum.

The unstable condition of the arm is illustrated in plan view in Figure 6, in which the line of pressure P of the hydraulic cylinder lies at an angle other than 90° to a line T tangential to the part of the former 16 upon which the shoe 37 is bearing, and consequently there is a component of force in the direction of the arrow F tending to swing the arm in a clockwise sense as seen in the figure.

The table 36 upon which the shoe 37 rests swings with the arm, but does not carry the shoe with it. Instead the shoe slides over the table, and the roller 42 begins to travel along the back of the shoe 37, and the consequential transfer of the position of application of pressure on the back of the shoe towards the other end thereof causes the shoe to roll slowly along the work-piece, swinging angularly as it does so but independently of the arm 23, so that the pressure of the shoe upon the work-piece is transferred gradually and progressively along the work-piece, and the metal is progressively shaped on to the male former 16. Owing to the fact that this shaping on to the former 16 is accompanied or immediately followed by compression of the metal of the work-piece between the shoe 37 and male former 16 over the whole cross-section of the work-piece as the shoe rolls thereon, the work is formed without producing any undesirable crinkles or distortion; the metal thickens up slightly on the inside of the curve but is not over-strained in any way.

It will be clear that if the whole of the work-piece were to be formed in a single step with the swinging arm moving continuously through a complete revolution, the shoe would have to be equal in length to the full developed length of the elliptical former profile and this would render the shoe prohibitively long in the present machine. In the present case, therefore, the work-piece is formed in four stages with a shoe which is equal in length to a little more than a quarter of the developed length of the former profile. In the first stage the fulcrum is moved along the path 54 to a position 55, and the arm 23 follows shaping the first quarter of the work-piece, until it arrives at a position shown in dotted line at 56. The pressure of the hydraulic cylinder 34 is then released and the shoe 37, which by now has its left-hand end between the roller 42 and the work-piece, is slid from right to left across the table 36 until its right-hand end is again between the roller 42 and work-piece in readiness for shaping the second quarter of the work. The pressure of the cylinder 34 is then again applied to the back of the shoe 37 and the fulcrum is moved rearwardly, and to the right, as viewed from the front of the machine, along a path 57 to a position 58 to perform the second stage of the forming operation, then forwardly and to the right along a path 59 to a position 60 for the third stage, and finally forwardly and to the left along a path 61 back to the position 53 for the fourth stage and to complete the cycle. The arm 23 is in the positions shown in dotted line at 62 and 63 when the fulcrum is at rest in positions 58 and 60 respectively, and in each position the pressure

of the cylinder 34 is released and the shoe 37 is slid from right to left across the table, as viewed looking along the arm 23 towards the fulcrum.

When the shaping of the work-piece has been completed, the pressure on the back of the shoe 37 is released and the shoe is removed from the work; the finished work can then be replaced by a fresh work-piece and the cycle of operations repeated. The former is collapsible, being made up from a number of sections detachable one from another, in order that it shall be capable of removal from the finished work-piece which surrounds it.

Thus, Figure 5 shows in plan an elliptical former made up of five separable sections 64, 65, 66, 67, 68, with disconnectable brackets 69 for holding the sections together, and it will be clear that after a double-flanged work-piece has been bent to shape around the former, the former may be removed by first knocking out the middle section 68 and then sliding first sections 66 and 67, and then sections 64 and 65, inwards.

It is to be understood that Figure 4 is merely a diagram for the purpose of explaining the working of the machine and that the path of the fulcrum shown is only an approximate one; moreover although the arm 23 is represented at 54, 62 and 63 as being in each case in a position normal to the horizontal centre-line of the work-piece and former at that point, this will not in actual fact be so, as the arm 23 always tends to lag behind the fulcrum in its swinging owing to the friction in the machine and the resistance of the work-piece to the shoe 37. This can be compensated for at the end of each cycle by carrying the fulcrum past the position 53 for a short distance in order to bring the arm 23 round in front of the machine far enough to complete the shaping of the work-piece; the fulcrum can then, if desired, be returned to the position 53 for commencement of the next working cycle.

Figure 3 shows in plan view the parts of the machine in the relative positions which they occupy near the completion of the shaping of the first quarter of the work-piece.

The pressure employed in forming the work-piece is high; it may be of the order of 2,000 lbs. per square inch. The hydraulic pressure is conveyed to the various cylinders of the machine by reinforced flexible pipes, not shown in the drawings. A constant delivery type pump is automatically controlled to maintain the working pressure in the various hydraulic circuits. An adjustable relief valve is provided in the pressure line to the swinging pressure cylinder 34 in order to prevent excessive fluid pressure in said cylinder during shaping of the work-piece.

It will be understood that, in a bending machine with an arm having a fixed fulcrum and provided with a pressure cylinder and a shoe similar to that of the present machine to roll on the work-piece, for example a machine as described in the above mentioned Patent No. 2,636,537, when the shoe is pressing the work-piece to a part of the former where the distance of the former profile from the pivot of the arm is increasing, there will be increased resistance to the progress of the swinging arm as compared with when the distance of the former profile from the pivot is constant, whereas when said distance is decreasing the resistance to swinging is decreased. These conditions under which the resistance to swinging is increased or decreased may be regarded as analogous to "uphill" or "downhill" movement of the shoe respectively. Although

the swinging arm in the present machine has a moving fulcrum, similar circumstances, dependent upon the curvature of the part of the former against which the shoe is pressing the work-piece, affect its movement; for example, the arm will tend to speed up when the shoe is shaping the first and third quarters of the work-piece and will be slowed down when forming the second and fourth quarters. The constant delivery pump and the aforementioned relief valve keep the pressure exerted by the cylinder 34 substantially constant whether the movement of the shoe 37 is "uphill" or "downhill," but it is also important to ensure that the movement of the arm 23 and shoe 37 should be sufficiently slow to allow the metal of the work-piece time to flow as it is shaped, and this may be effected either by varying the path of the fulcrum or by slowing up the fulcrum movement over the parts of its path which it traverses when the shoe is moving "downhill" so that unduly rapid folding action upon the work-piece is prevented from occurring at any point in the cycle.

Although a particular machine and the production of a specific form of work is described herein by way of example, it will be appreciated that considerable modification and addition is possible without departing from the scope of the invention.

In most cases it is desired to clamp the work-piece to the former at some stage in the operation and often throughout the bending and shaping operation and for this purpose a hydraulic clamp such as that upon the machine described in the above mentioned Patent No. 2,636,537, or a number of such clamps, could be provided. If desired, an auxiliary shoe control hydraulic cylinder as described in said co-pending application may be carried by the swinging arm to assist in swinging the shoe angularly and in pulling the shoe off the work, to which it may tend to stick.

I claim:

1. In a metal-working machine the combination of a machine frame, a former secured on said frame and having a front face to receive a work-piece for shaping, an elongated arm mounted on the frame to be capable of swinging in front of the former about a fulcrum located behind the former in a manner to change the crossing angle of the longitudinal arm axis and the former profile, said fulcrum being movable upon the machine frame in the plane in which the arm swings about said fulcrum to afford pivotal movement of the arm about different parallel axes, a press-member supported in front of the former to bear on a work-piece placed against the former, fluid-pressure-operated means mounted on the arm to urge the press-member toward the former, and fulcrum-moving means mounted upon the machine frame and operatively connected to the arm at the fulcrum end thereof behind the former for moving said fulcrum to various positions behind the former to cause the arm, under the effect of pressure applied to the work-piece by the fluid-pressure-operated means and press-member, to swing and shift the place of application of pressure progressively along the workpiece.

2. In a metal-working machine the combination of a machine frame, a former secured on said frame and having a curved front face to receive a workpiece for shaping, an arm mounted on the frame to swing in front of the former about a pivot pin located behind the former, a fulcrum block in which the pivot pin is journalled which block is mounted to slide upon the frame in any

direction in the plane in which the arm swings about such pivot pin to afford pivotal movement of the arm about different parallel axes, a press-member supported in front of the former to bear on a workpiece placed against the former, fluid-pressure-operated means mounted on the arm to urge the press-member toward the former, and fulcrum-moving means mounted upon the machine frame and operatively connected to the fulcrum block for sliding it to various positions to cause the arm, when pressure is applied to the workpiece by the fluid-pressure-operated means and press-member, to swing and shift the place of application of pressure progressively along the workpiece.

3. In a metal-working machine the combination of a machine frame, a former secured on said frame and having a curved front face to receive a workpiece for shaping, an arm mounted on the frame in front of the former to swing about a fulcrum located behind the former, said fulcrum being movable upon the machine frame in the plane in which the arm swings about said fulcrum to afford pivotal movement of the arm about different parallel axes, a shoe supported in front of the former and able to roll on a workpiece placed against the former, fluid-pressure-operated means mounted on the arm to press the shoe against the workpiece on the former, said fluid-pressure-operated means being provided with a nose to apply the pressure to the shoe which nose moves laterally as the arm swings, thereby shifting the place of contact between nose and shoe along the shoe, and fulcrum-moving means mounted upon the machine frame and operatively connected with the fulcrum of the arm for moving said fulcrum to various positions behind the former to cause the arm, when pressure is applied to the workpiece by the fluid-pressure-operated means and shoe, to swing and effect said lateral movement of the nose to shift the place of application of pressure to the workpiece by the shoe progressively along the workpiece.

4. In a metal-working machine the combination of a machine frame, a former secured on said frame and having a curved front face to receive a workpiece for shaping, a flat table mounted in front and below the level of the former, an arm mounted on the frame to swing in front of the former in a horizontal plane about a fulcrum located behind the former, said fulcrum being movable upon the machine frame in the plane in which the arm swings about said fulcrum to afford pivotal movement of the arm about different parallel axes, a shoe able to roll in a horizontal plane of movement on a workpiece placed against the former which shoe rests on the table and is capable of being slid over it linearly and angularly in any direction, fluid-pressure-operated means mounted on the arm to press the shoe against the workpiece on the former, said fluid-pressure-operated means being provided with a nose to apply the pressure to the shoe which nose moves laterally as the arm swings, thereby shifting the place of contact between nose and shoe along the shoe, and fulcrum-moving means mounted upon the machine frame and operatively connected with the fulcrum of the arm for moving said fulcrum to various positions behind the former to cause the arm, when pressure is applied to the workpiece by the fluid-pressure-operated means and shoe, to swing and effect said lateral movement of the nose to shift the place of application of pressure to the workpiece by the shoe progressively along the workpiece.

10 to the workpiece by the shoe progressively along the workpiece.

5. In a metal-working machine the combination of a machine frame, a former secured on said frame and having a curved front face to receive a workpiece for shaping, an arm mounted on the frame to swing in front of the former and in a horizontal plane about a fulcrum located behind the former, said fulcrum being movable upon the machine frame in the plane in which the arm swings about said fulcrum to afford pivotal movement of the arm about different parallel axes, a flat table on the arm below the former, a shoe able to roll in a horizontal plane of movement on a workpiece placed against the former which shoe rests on the table and is capable of being slid over it linearly and angularly in any direction, a hydraulic piston and cylinder unit mounted on the arm to press the shoe against the workpiece on the former, said piston and cylinder unit being provided with a nose to apply the pressure to the shoe which nose moves laterally as the arm swings thereby shifting the place of contact between nose and shoe along the shoe, and fulcrum-moving means mounted upon the machine frame and operatively connected with the fulcrum of the arm for moving said fulcrum to various positions behind the former to cause the arm, when pressure is applied to the workpiece by the piston and cylinder unit and shoe, to swing and effect said lateral movement of the nose to shift the place of application of pressure to the workpiece by the shoe progressively along the workpiece.

6. In a metal-working machine the combination of a machine frame, a former secured on said frame and having a curved front face to receive a workpiece for shaping, an arm mounted on the frame to swing in front of the former in a horizontal plane about a pivot pin located behind the former, a fulcrum block in which the pivot pin is journalled, which block is mounted to slide upon the frame in any direction in the plane in which the arm swings about said pivot pin to afford pivotal movement of the arm about different parallel axes, a flat table on the arm below the former, a shoe able to roll in a horizontal plane of movement on a workpiece placed against the former which shoe rests on the table and is capable of being slid over it linearly and angularly in any direction, a hydraulic piston and cylinder unit mounted on the arm to press the shoe against the workpiece on the former, said piston and cylinder unit being provided with a roller nose to apply the pressure to the shoe, which roller nose moves laterally as the arm swings thereby shifting the place of contact between nose and shoe along the shoe, and fulcrum-moving means mounted upon the machine frame and operatively connected to the fulcrum block for sliding it to various positions to cause the arm, when pressure is applied to the workpiece by the piston and cylinder unit and shoe, to swing and effect said lateral movement of the roller nose to shift the place of application of pressure to the workpiece by the shoe progressively along the workpiece.

7. In a metal-working machine the combination of a machine frame, a former secured on said frame and having a curved front face to receive a workpiece for shaping, an arm mounted on the frame to swing in front of the former about a pivot pin located behind the former, a fulcrum block in which the pivot pin is journalled, which block is mounted to slide between

guide plates upon the frame in any direction in the plane in which the arm swings about such pivot pin to afford pivotal movement of the arm about different parallel axes, a press-member supported in front of the former to bear on a workpiece placed against the former, fluid-pressure-operated means mounted on the arm to urge the press-member toward the former, and a pair of hydraulic piston and cylinder units mounted upon the machine frame with their axes lying substantially at right angles to one another in the plane of movement of the fulcrum block, said piston and cylinder units being operatively connected to the fulcrum block for sliding it to various positions to cause the arm, when pressure is applied to the workpiece by the fluid-pressure-operated means and press-member, to swing and shift the place of application of pressure progressively along the workpiece.

8. In a metal-working machine the combination of a machine frame, a former secured on said frame and having a curved front face to receive a workpiece for shaping, an arm mounted on the frame to swing in front of the former in a horizontal plane about a pivot pin located behind the former, a fulcrum block in which the pivot pin is journalled, which block is mounted to slide horizontally between guide plates upon the frame in any direction to afford pivotal movement of the arm about different parallel axes, the flat table on the arm below the former, a shoe able to roll in a horizontal plane of movement on a workpiece placed against the former, which shoe rests on the table and is capable of being slid over it linearly and angularly in any direction, a main hydraulic piston and cylinder unit mounted on the arm to press the shoe against the workpiece on the former, said main piston and cylinder unit being provided with a roller nose to apply the pressure to the shoe, which nose moves laterally as the arm swings thereby shifting the place of contact between roller nose and shoe along the shoe, and a pair of fulcrum-moving hydraulic piston and cylinder units mounted upon the machine frame with their axes lying substantially at right angles to one another in a horizontal plane, said fulcrum-moving piston and cylinder units being operatively connected to the fulcrum block for sliding it to various positions to cause the arm, when pressure is applied to the workpiece by the main piston cylinder unit and shoe, to swing and effect said lateral movement of the roller nose to shift the place of application of pressure to the workpiece by the shoe progressively along the workpiece.

9. In a metal-working machine the combination of a machine frame comprising a base, supports upstanding from the base and a bridge member extending transversely of the machine between the supports and above the base, a former support member depending from the bridge member, a former secured above the base upon the lower end of the former support member, said former having a curved profiled face to receive a workpiece for shaping, which profiled face extends endlessly all around the former so that said face is in the form of a closed figure, an elongated arm mounted on the frame to be capable of swinging in a horizontal plane about a fulcrum located within the closed figure of the profiled face of the former in a manner to change the crossing angle of the longitudinal arm axis and the former profile and through a complete revolution around the former, said fulcrum being movable upon the machine frame in the horizontal plane to afford

5 pivotal movement of the arm about different parallel axes, a press-member supported on the arm to bear on a workpiece placed against the former, fluid-pressure-operated means mounted on the arm to urge the press-member toward the former, and fulcrum-moving means mounted upon the machine frame and operatively connected to the arm at the fulcrum end thereof within the closed figure of the profiled face of the former for moving said fulcrum to various positions within the closed figure of the profiled face of the former to cause the arm, under the effect of pressure applied to the workpiece by the fluid-pressure-operated means and press-member, to swing and shift the place of application of pressure progressively along the workpiece.

10. In a metal-working machine the combination of a machine frame comprising a base, supports upstanding from the base and a bridge-member extending transversely of the machine between the supports and above the base, a former support member depending from the bridge-member, a former secured above the base upon the lower end of the former support member, said former having a curved profiled face to receive a workpiece for shaping, which profiled face extends endlessly all around the former so that such face is in the form of a closed figure, an arm mounted on the frame to swing in a horizontal plane through a complete revolution around the former about a pivot pin located within the closed figure of the profiled face of the former, a fulcrum block in which the pivot pin is journalled, which block is mounted to slide horizontally between guide plates upon the frame in any direction to afford pivotal movement of the arm about different parallel axes, a flat table on the arm below the former, a shoe able to roll in a horizontal plane of movement on a workpiece placed against the former, which shoe rests on the table and is capable of being slid over it linearly and angularly in any direction, a main hydraulic piston and cylinder unit mounted on the arm to press the shoe against the workpiece on the former, said main piston and cylinder unit being provided with a roller nose to apply the pressure to the shoe which nose moves laterally as the arm swings thereby shifting the place of contact between roller nose and shoe along the shoe, and a pair of fulcrum-moving hydraulic piston and cylinder units mounted upon the machine frame with their axes lying substantially at right angles to one another in a horizontal plane, said fulcrum-moving piston and cylinder units being operatively connected to the fulcrum block for sliding it to various positions within the closed figure of the profiled face of the former to cause the arm, when pressure is applied to the workpiece by the main piston and cylinder unit and shoe, to swing and effect said lateral movement of the roller nose to shift the place of application of pressure to the workpiece by the shoe progressively along the workpiece.
